[57] CLAIM

The ornamental design for an ankle element, as shown and described.

DESCRIPTION

FIG. 1 is a right and rear side elevational view of an ankle element showing my new design;

FIG. 2 is a front view thereof;

FIG. 3 is a top view thereof;

FIG. 4 is a left side view thereof;

FIG. 5 is a rear view thereof; and,

FIG. 6 is a bottom view thereof.

The broken line showing of a shoe upper and sole in the figures is for illustrative purposes only and forms no part of the claimed design.

FIG. 1

FIG. 2

FIG. 3

FIG. 4

FIG. 5

FIG. 6
